GARMENT

Mina Wallace, Rockford, Ill.

Application December 27, 1932, Serial No. 649,064

3 Claims. (Cl. 2—80)

This invention relates to an improved outer garment for children and seeks, among other objects, to provide a garment in the form of a union suit embodying a coat and trousers which

5 may be worn for protecting a child in severe weather or while playing in the snow.

A further object of the invention is to provide a union suit of the character indicated so constructed that the suit may be readily put on and 10 as easily taken off.

A further object of the invention is to provide a union suit embodying a front section extending from the neck to the lower ends of the legs and wherein said section may be released at its outer 15 longitudinal edges throughout the entire length thereof so that the garment may be put on like a coat, brought about the ankles and closed by "zpper" fastenings.

And the invention seeks, as a still further object, to provide a garment wherein the upper portion of the front section may be released and dropped down for opening the coat to afford ventilation when so desired while the legs of the garment will remain closed.

20 Other and incidental objects of the invention, not specifically mentioned in the foregoing, will be apparent during the course of the following description.

In the accompanying drawings forming a part 25 of this application,

Figure 1 is a front elevation of my improved garment showing the front section closed.

Figure 2 is a view similar to Figure 1 showing the front section partially open.

30 Figure 3 is a rear elevation of the garment.

Figure 4 is a fragmentary rear elevation showing the seat dropped down, and

Figure 5 is a detail section on the line 5—5 of Figure 3.

40 My improved garment is in the form of a union suit and embodies a combined coat and trousers. As seen in Figure 3, the back 10 of the coat is preferably formed of a single piece of cloth while front pieces 11, each of a single piece of cloth, 45 are provided at the front of the coat. The front pieces 11 are secured to the back 10 along the upper edges of the tops of the shoulders and below the armholes of the garment and these parts carry the sleeves 12 preferably equipped

50 with knit cuffs 13. A suitable neck opening is provided and surrounding said opening is a collar 14 secured to the back 10 and front pieces 11. Sewed to the exposed margins of the front pieces 11 at their upper ends are overlapping throat 55 flaps 15 one of which may be provided with a

button and the other with a button hole, as indicated at 16, for detachably connecting said flaps and securing the collar 14 about the neck of the wearer.

As shown in Figure 4, the back 10 of the coat 60 terminates in a curved edge slightly below the waist of the garment and is equipped with a row of buttons 17. The front pieces 11 at the front of the coat, however, extend below the waist line, as particularly seen in Figures 1 and 2 of the 65 drawings, and are provided with tapered lower end portions 18. Secured to the rear edges of the lower end portions 18 of the pieces 11 are the back pieces 19 of the legs of the garment. The pieces 19 are each preferably formed of a 70 single strip of cloth and, as seen in Figure 3, are widened at their upper ends and united along the crotch line of the garment to provide a seat 20, free at its upper end as well as free for a distance 75 at its side edges. Extending transversely at the upper end of the seat 20, as particularly seen in Figure 5, is an inner facing strip 21 and piercing said strip and the top margin of the seat are button holes 22 adapted to receive the buttons 17 for securing the seat closed. Sewed to the upper 80 edge portion of the seat, above the row of button holes 22, is a flap 23 adapted to fold down over the row of buttons 17 for concealing said buttons and, as illustrated in Figures 2 and 3, this flap is provided at its ends with ears 24 which are 85 provided with button holes to receive buttons 25 on the front pieces 11 of the garment for normally securing the flap in folded position.

As will now be seen, the back 10, front pieces 90 11 and the back pieces 19 of the legs and their attached parts provide the body section of the garment and mating with said body section is a front section releasable along its longitudinal edges as will presently appear. This front section is composed of front pieces 26 each preferably formed from a single piece of cloth and, as will be observed, said front pieces are of a 95 length to extend from the neck to the lower ends of the legs. The lower end portions of said front pieces are secured at their inner edges to the inner edges of the back pieces 19 along the inner sides of the legs whence the confronting edges of the pieces 26 are united by a seam 27 extending from the crotch to the upper ends of said pieces. The upper end of the front section 100 of the garment thus provides the front portion of the coat while the bifurcated lower end of the front section provides the front portions of the legs of the garment. Secured to the front section, adjacent the waist line, is a patch 28 di- 105 110

vided by a seam 29 to provide a pair of pockets.

At their lower ends, the legs carry preferably knitted cuffs 30 split at the outer sides of the legs in line with the outer free edges of the front section of the garment and it is now to be noted that these edges of said sections are curved longitudinally to mate with the confronting similarly curved edges of the body section of the garment, said confronting edges starting at the outer sides 10 of the legs and thence extending upwardly on diagonal lines across the front of the garment to the neck, the front section of the garment being tapered towards its upper end. These confronting edges of the garment are preferably connected 15 by conventional "zipper" fastenings 31, which fastenings extend across the cuffs for normally holding the garment closed. Other approved fastenings may, however, be substituted for the "zipper" fastenings, if so desired.

20 As will now be seen, by releasing the "zipper" fastenings 31, the front section of the garment may be freed from top to bottom so that after the flaps 15 are disconnected, the garment may be put on like a coat after which the fastenings 25 31 may be readily re-united for closing the garment and securing it in place. As suggested in Figure 2, however, the upper portions of the fastenings 31 may be released for any desired distance and thus free the upper portion of the 30 front section of the garment to provide ventilation when so desired, without likelihood of the garment becoming displaced from the wearer.

Having thus described the invention, I claim:

1. A union suit embodying a combined coat and 35 trousers split along lines diverging from the neck of the coat downwardly across the trouser legs to provide a body section and a mating front section, the body section being formed with a seat free at its upper end, fastenings normally securing 40 the seat closed, a flap carried by the upper

end of the seat and normally folded over said fastenings when the seat is closed, the flap being provided at its ends with ears, fastenings anchoring said ears and normally securing the flap folded, and means releasably connecting the free margins of said sections. 80

2. A union suit comprising a combined coat and trousers, the trousers being formed with a seat free at its upper end and the coat having its lower end overlapped by the upper end of the 85 seat when the seat is in a raised position, fasteners carried by the lower portion of the back for engaging through the upper end portion of the seat to releasably hold the seat raised, a flap extending along the upper edge of the seat and adapted to be folded outwardly and downwardly against the seat to cover said fasteners, said flap having its end portions extending from sides of the seat when folded to form tabs, and means for 90 releasably securing the tabs to the coat. 95

3. A union suit comprising a combined coat and trousers, said suit having sections spaced transversely at the front of the suit and defining a front opening extending the full length of the suit from the neck opening of the coat to lower ends 100 of legs of the trousers, flaps extending toward each other from upper portions of spaced sections of the coat and adapted to be releasably secured in overlapping relation to each other to close the neck opening of the coat at the front and provide a chest shield, a front section for closing the front opening of the suit, and means for detachably securing side edges of the front section to side edges of said spaced portions of the suit for the full length thereof with the upper 110 end portion of the front section overlying said flaps and terminating at the neck opening when secured. 105
